UNITED STATES PATENT OFFICE

2,548,902

HYDRAULIC JACK

Joseph J. Mueller, St. Joseph, Mich., assignor to
 Auto Specialties Manufacturing Company, St.
 Joseph, Mich., a corporation of Michigan

Application November 17, 1945, Serial No. 629,241

9 Claims. (Cl. 60—52)

1

This invention relates to hydraulic jacks.

One of the objects of the present invention is to provide an improved type of release valve structure which will enable a more accurate and gradual control for the descent of the ram upon opening of the release valve.

Yet another object of the invention resides in providing a release valve structure which is an improvement over prior constructions, whereby a slower and better controlled descent of the ram may be secured.

Yet another object of my invention resides in providing a release valve structure wherein the springs used for controlling the valves, such as ball valves, are eliminated.

Yet another object of my invention resides in providing a release valve structure composed of the minimum number of machine operations formed upon a base or other metallic housing and including a release valve structure to enter said borings, including a pair of ball valves and a manually turnable release valve.

These and other objects of the invention will be apparent from a perusal of the following specification when taken in connection with the accompanying drawings, wherein:

Figure 1 is a vertical sectional view taken through the jack on the line 1—1 of Figure 3;

Figure 2 is a side view of the jack with the operating means shown in section and taken on the line 2—2 of Figure 1;

Figure 3 is a plan section taken on the line 3—3 of Figure 4;

Figure 4 is a section taken on the line 4—4 of Figure 3;

Figure 5 is a plan section with the valve removed; and

Figure 6 is a perspective view of the valve sleeve or insert.

Referring now to the drawings in detail, the invention is illustrated as applied to a particular type of jack, but it is to be understood that the invention is adaptable to other types of hydraulic jacks wherein the release valve construction herein disclosed cooperates with the hydraulic passages and the valves for controlling the passage of liquid from the reservoir to the high pressure pump cylinder and from the high pressure pump cylinder to the ram cylinder and from the ram cylinder back to the reservoir, the latter being controlled by the release valve.

For purposes of illustration, but not by way of limitation, I have shown the improved form of my invention as applied to a jack having a base 2 provided on its upper face with a relatively large bor-

2

ing 4 terminating in a smaller boring 6 forming a well disposed centrally of the boring 4. The inner wall of the boring 4 is threaded as at 8 to receive an upstanding stationary ram cylinder 10. In addition, the base 2 is slightly countersunk as at 12 and provided with the shoulder 14 which receives interiorly thereof a second outer sleeve 16 to form between it and the sleeve 10 a reservoir 18. The outer end of the ram cylinder sleeve 10 is provided with threads 20 whereby threadedly to receive a cap having an outer depending curved sleeve 22 and an inner sleeve 24 which is spaced inwardly of the outer sleeve 22. The inner wall of this inner sleeve is threaded as at 26 so that the threads thereof engage the threads 26 of the ram sleeve 10. It will be noted that the inner wall 28 of the sleeve part 24 stands outwardly circumferentially of the ram cylinder sleeve 10 so as to receive therein a packing ring 30 which holds a packing 32 in position against the end of the ram sleeve 10 and against the inner wall of the inner ram sleeve 24. By screwing the sleeve onto the threads 20 of the ram sleeve 10 the end 34 of the sleeve 22 will engage circumferential shoulder 36 on the end of the reservoir sleeve 16 whereby to clamp the same firmly in position against the shoulder 14 of the base 2 whereby the reservoir sleeve 16 is held securely in position.

A ram 38 is reciprocable within the ram sleeve 10. This ram sleeve has on its lower end the usual type of leather gasket or liquid sealing ring 40 held in position thereon by suitable fastening means such as 42 as is well known in the art. The outer end of the ram 38 is bored as at 44 and the outermost end of this ram 38 is provided with threads as at 46 threadedly to receive the threads 48 on a ram extension having a load carrying head 50.

In like manner the base 2 is also provided with an opening 52 having threaded internal walls 54 adapted to receive a sleeve 56 likewise threaded as at 58 to screw into the threaded opening 52 of the base. This constitutes the high pressure pump cylinder. In this high pressure pump cylinder reciprocates a high pressure pump piston 60 which on its end is provided with the usual packing or other gasket 62 and at its outer end is provided with a bore 64 through which is inserted a cross pin 66 which is carried by the bifurcations 50 of a head 68 carried by a socket 70. This socket is pivoted as at 72 and has an opening as at 74 for a handle. The pivot member 72 is connected by means of a link 76 which is pivoted as at 78 to the base 2 whereby upon reciprocation of the socket 70 by means of its pivotal connection 72

with link 76 pivoted to the base as at 18, the high pressure pump piston 60 will be reciprocated in its cylinder. The outer sleeve 16 is provided with an opening 80 normally closed by a threaded plug 82 for filling the reservoir with oil or other liquid means. A ring cap 84 threads as at 86 onto the outer threaded end of the high pressure pump cylinder 56 to close the same and the piston 60 reciprocates through this threaded cap ring 84. The pin 66 is held in position by any type of cotter pin 88, as shown.

The base 2 of the jack is provided with suitable liquid conduits through which the liquid is passed from the reservoir 18 to the high pressure pump cylinder beneath the piston thereof and thence from this high pressure pump cylinder to the ram cylinder well 6 to raise the ram 38, and also from the ram cylinder well 6 back to the reservoir for the purpose of releasing the ram to let the ram descend. In the present instance the base 2 is provided with a pair of preferably parallel conduits 90 and 92. The conduit 90 opens onto the outer face of the base but the interior of this conduit is of smaller diameter as at 94. It terminates as at 96 and connects with the transversely disposed release valve bore hereinafter described. The bore 92 is provided with an interiorly disposed smaller bore extension 98 which extends as at 126 all the way into the ram cylinder well 6, see Figure 1. This bore does not connect with the high pressure pump cylinder. The bore 94 however, as shown in Figure 2, is provided with the lateral or upstanding passage 102 which does connect with the base of the high pressure pump cylinder 56.

Formed in the base transversely to the two passages 94 and 98 is a release valve bore shown in Figures 3, 4 and 5. The outer end of this bore opens onto a countersunk portion 104 formed on the exterior face of the base. The outer end of the bore is threaded as at 106 and the extension portion 108 is preferably of the same diameter except that it is not threaded. Still another extension portion 110 of this release valve bore is formed of smaller diameter and to provide a valve seat 112, and yet another further extension 96 of this release valve bore terminates in a second valve seat 116, while still another smaller projection 118 of this bore terminates as at 128 within the metal of the base. The portion 118 of smallest diameter of the bore connects by means of an upwardly projecting bore 122 with the hydraulic reservoir 18. The bore 94, see Figure 5, connects with the portion 96 of the release valve bore at 124. The bore 98 connects with that portion 110 of the release valve bore, see Figures 4 and 5.

The valve seat 116 is normally closed by a ball valve 128 and the valve seat 112 is normally closed by a ball valve 130.

A release valve mechanism, see Figure 6, is provided, which includes a sleeve 132 having a central passageway 134. This passageway 134 in turn is provided with an extension bore 136 of smaller dimension which provides a release valve seat 137 internally thereof. The bore 136 is connected by means of a cross groove 138 (see Figure 6) which extends clear across the end face of the sleeve. The sleeve has a bevelled surface at its inner end 140 which fits exactly into a corresponding bevelled surface or seat on the inner wall of the release valve bore. The sleeve 132 is provided with a lateral port 142 which connects the opening 134 through the sleeve with a passageway 144 formed in the base 2 and which con-

nects with the reservoir 18. A metallic threaded packing nut 146 threadedly engages the threads 106 of the outer portion of the bore and holds packing 148 firmly in position between the nut 146 and the outer end 150 of the sleeve 132.

The internal, circular wall of this packing nut 146 is threaded as at 152 to receive the threaded portion 154 of a release valve proper 156. The shank 158 of this release valve rod is pointed at its inner end to seat upon the seat 137 formed interiorly of the valve sleeve 132. By means of this construction, when the release valve 156 is in inward or closed position and the high pressure pump piston 60 is drawn upwardly, liquid will be sucked from the reservoir 18 through the passage 122 into the bore 118, the smaller ball 128 leaving its seat 116. This liquid will thence pass from the bore 96 of the release valve bore through the bore 98, thence through the bore 102 into the high pressure pump cylinder 52. On the down stroke of the pump piston 60 this liquid will then be forced downwardly and the liquid will then pass back through the port 94, and force the ball 128 back onto its seat, and at the same time will force the ball 130 from its seat so that therefore this liquid will then pass into the next larger bore 110 of the release valve bore and thence by means of the passage 126 into the ram cylinder 4 to raise the ram. The reciprocating cycle of the piston is continued until the ram is raised to the desired height. When it is desired to lower the ram the release valve spindle 154 is turned to move the release valve shank 158 outwardly off its valve seat 137 at which time liquid will pass from the ram cylinder 4 through the passage 126 to the bore 110, thence through the groove 138 and also through the conduit 136 past the now open conical valve end and the valve seat 137, thence into the passage 144 to the reservoir 18.

By thus forming the release valve with the sleeve 132 I am enabled to reduce the number of borings in the release valve bore and I am likewise enabled to provide a much finer control of liquid from the ram cylinder back into the reservoir due to the fact that the liquid must flow through the restricted opening 136 in the release valve sleeve and past the relatively small valve seat 137. The groove 138 prevents the ball 130 from seating upon the end of the conduit 136 and sealing it. I have found, in this construction, that I am enabled to eliminate the use of springs between the balls 130 and 128 and between the ball 130 and the end of the sleeve 132. The foregoing construction provides a very nicely controlled descent for the ram of the hydraulic cylinder, eliminates parts, and eliminates the number of borings required in forming the release valve structure.

Obviously the invention is not limited to the specific details of construction disclosed herein but is capable of other modifications and changes without departing from the spirit and scope of the appended claims.

Having thus described the invention, what I claim as new and desire to secure by Letters Patent is:

1. An hydraulically actuated mechanism comprising a base, a ram cylinder and a reservoir associated with the base, a high pressure pump cylinder associated with the base, a piston reciprocable in said pump cylinder, said base having a bore formed therein, said bore substantially at its inner end being connected with the

reservoir, and the opposite or outer end of the bore opening onto the surface of the base, said bore being formed intermediate its ends with a pair of spaced valve seats, valves adapted to be normally closing on said seats, said bore between said valves being provided with a liquid connection to the high pressure pump cylinder, and said bore between its outer end and the adjacent valve seat being provided with a passage connected with the ram cylinder and said bore between its outer end and said last mentioned passage being provided with a connection to the reservoir, and means disposed in the outer end of said bore and forming a liquid release passage between the passage in the bore connecting with the ram cylinder and the passage in the bore forming the outermost connection with the reservoir, and a shiftable release valve for controlling the opening and closing of said release passage.

2. An hydraulic jack comprising a base, a ram cylinder and a reservoir associated with the base, a ram in said ram cylinder, a high pressure pump cylinder associated with the base, a piston reciprocable in said pump cylinder, said base having a bore formed therein, said bore substantially at one end thereof being connected with the reservoir and the opposite outer, larger end of the bore opening onto the surface of the base, a sleeve disposed in the outer end of said bore, said bore being formed with a pair of spaced valve seats, spaced valves adapted to be disposed normally on said seats controlling the passage of liquid from the reservoir to the pump and from the pump to the ram cylinder, said bore between said valves being provided with a liquid connection to the high pressure pump cylinder, said bore between its outer, larger end and the nearer valve seat being provided with a passage connected with the ram cylinder, and said bore between said last mentioned passage and its outer, larger end being provided with a connection with the reservoir, said sleeve mounted in said bore and forming a valve seat of substantially smaller cross section than the cross section of the bore and connecting said last mentioned connection with that part of the bore in which is located the connection to the ram cylinder, and a release valve associated with the means mounted in said bore and adapted to control said valve seat of restricted cross section whereby to permit liquid of controlled restricted amounts to pass from the ram cylinder back into the reservoir through said bore.

3. An hydraulic jack comprising a base, means forming a reservoir and a ram cylinder on said base, means on the base forming a high pressure pump cylinder, a piston in said pump cylinder, said base having a bore formed therein, the end of said bore of greater diameter opening onto the face of the base, and said bore being provided from its larger, outer end to its opposite closed end with stepped portions of restricted diameter providing a plurality of valve seats, means forming a connection from the portion of most restricted diameter to the reservoir, a hollow sleeve in the portion of largest diameter, a packing holding said sleeve in position and a packing ring holding said packing in position, said sleeve having an opening through its walls, a conduit in the base connecting said opening in the sleeve with the reservoir, said hollow sleeve having an opening through its innermost end which connects with the interior of the sleeve, and a release valve passing through said packing

ring and packing and through said hollow sleeve and controlling the restricted opening in the end of said sleeve, that inner, more restricted portion of the bore beyond the open end of said sleeve being provided with a passageway connecting with the ram cylinder and having two spaced apart valve seats between said passageway and the reservoir connection at the smaller end of said bore, valves adapted to rest on said seats to close the same, that portion of the bore between said valve seats having a connection with the high pressure pump cylinder.

4. An hydraulic jack comprising a base having a flat top, said top being formed with a main circular opening providing a circular well and with a spaced opening providing a high pressure pump cylinder well, a sleeve in said circular cylinder well to provide a ram cylinder and a sleeve associated therewith providing a surrounding liquid reservoir, a high pressure pump cylinder in said mentioned spaced opening, a piston reciprocable therein, a bore formed in a side wall of said base below the plane of the top of said base and substantially at a downward inclination, the larger outer end of said bore opening on the side wall of said base, a portion of the innermost end of said bore having a liquid connection with the liquid reservoir and an outer portion of larger diameter of said bore likewise connecting with the liquid reservoir, said bore between said spaced connections to the liquid reservoir being provided with spaced apart valve seats, valves normally resting on said seats, said bore between said seats being provided with a connection with the high pressure pump cylinder, and said bore between its outer end of larger diameter and the nearer valve seat being formed with a connection to the ram cylinder, and a sleeve disposed in said bore between the point at which the ram cylinder is connected and the outer end of larger diameter of the bore, said sleeve being hollow and with its innermost end provided with a restricted orifice, said sleeve having an opening registering with the port connecting said bore and the liquid reservoir, a packing ring threading into the outer threaded end of said bore, and a packing confined by said ring between said ring and said sleeve, and a release valve having its outer end threading into said packing ring and having a shank formed conically on the inner end to engage in the restricted opening in the end of said sleeve to close the same, the innermost end of said sleeve being provided with a cross groove connecting with the restricted opening in the end of said sleeve.

5. An hydraulically actuated mechanism comprising a base, a ram cylinder and a reservoir associated with the base, a high pressure pump cylinder associated with the base, a piston reciprocable in said pump cylinder, said base having a bore formed therein, the outer end of the bore opening onto the surface of the base, said bore substantially at its outer end connecting with the reservoir, said bore being formed intermediate its ends with a pair of spaced valve seats, valves adapted to be normally closing on said seats, said bore between said valves being provided with a liquid connection to the high pressure pump cylinder, and said bore between its outer end and the nearer valve seat being provided with a passage connected with the ram cylinder, and said bore between its outer end and said last mentioned passage being provided with a connection to the reservoir, and a manually shiftable release valve mechanism

mounted in the outer portion of said bore and providing a release valve passage between the ram cylinder and the reservoir of considerably less cross section than the outer portion of the bore.

6. An hydraulically actuated mechanism comprising a base, a ram cylinder and a reservoir associated with the base, a high pressure pump cylinder associated with the base, a piston reciprocable in said pump cylinder, said base having a bore formed therein, said bore substantially at a first end thereof being connected with the reservoir and the opposite or second end of the bore opening onto the surface of the base, said bore being formed intermediate its ends with a pair of spaced valve seats, valves adapted to be normally closing on said seats, said bore between said valves being provided with a liquid connection to the high pressure pump cylinder, and said bore between its second end and the nearer valve seat being provided with a passage connected with the ram cylinder, and said bore between its second end and said last mentioned passage being provided with a connection to the reservoir, a hollow sleeve mounted in the outer portion of the bore, said sleeve having a connection registering with the last mentioned connection with the reservoir and likewise having an opening connecting with the passage to the ram cylinder, and a manually shiftable release valve controlling said last mentioned passage in the sleeve, said release valve being shiftable relatively to said sleeve from a point externally of said base.

7. In an hydraulic jack or the like, in combination with a base, a liquid reservoir, a ram cylinder, a high pressure pump associated with the base, said base having formed therein a bore having its central axis extending in a straight line into the base from the outer wall of the base, inner portions of the bore providing a pair of spaced valve seats, a valve on each of said valve seats, there being a liquid connection from substantially the innermost end of said bore to the reservoir and there being a liquid connection from that portion of the bore between the two valves when on their seats to the high pressure pump cylinder, there also being a liquid connection from that part of the bore between the outermost valve and the outer end of the bore to the ram cylinder, and a release valve mechanism mounted in the outer end of said bore, said release valve mechanism including a liquid connection from the reservoir to the ram cylinder, said release valve mechanism including a shiftable release valve controlling said last mentioned connection, and said release valve being detachably mounted in the outer end of said bore so that upon removal of said release valve mechanism said valves are immediately accessible for removal.

8. In an hydraulic mechanism, in combination with a base, a ram cylinder, a high pressure pump and a liquid reservoir associated with said base, said base having a bore formed therein the central axis of which is substantially a straight line, the outer end of said bore opening upon the exterior walls of said base, inner portions of said bore being formed with spaced valve seats, separate valve means normally seating upon said seats, conduits controlled by said valves and interconnecting the reservoir with the ram cylinder and with the high pressure pump cylinder, and a release valve mechanism detachably mounted in the outer end of said bore so that upon removal of said release valve mechanism said spaced valves are immediately accessible for removal through said substantially straight bore, said release valve mechanism including a shiftable member, and a fluid connection between the ram cylinder and the reservoir controlled by the movement of said release valve.

9. An hydraulic jack comprising a base, a ram cylinder mounted thereon, means on the base forming a reservoir associated with the ram cylinder, a ram in said cylinder, a high pressure pump cylinder mounted on the base and a piston reciprocable in said pump cylinder, said base having an elongated bore formed therein, liquid passages formed in said base, means forming a plurality of valve seats disposed in spaced relation in and longitudinally of said bore, one of said valve seats being a pressure release valve seat, a pressure release valve adjustably disposed in said bore for closing the outer end thereof in liquid-tight relation to the walls of said bore and shiftable to shift said release valve relatively to its seat to control the flow of liquid between the ram cylinder and the reservoir, and additional valve means movably mounted in said bore beyond said release valve and adapted to seat and unseat from certain of the spaced valve seats of said bore for controlling the liquid flow from the reservoir to said pump cylinder and from said pump cylinder to said ram cylinder upon reciprocation of the pump piston.
